(57) **CLAIM**

The ornamental design for a portion of a display screen with an animated graphical user interface, as shown and described.

DESCRIPTION

FIG. 1 is a front view of a first image of a first embodiment of a portion of a display screen with an animated graphical user interface showing my new design;

FIG. 2 is a front view of a second image thereof;

FIG. 3 is a front view of a first image of a second embodiment of a portion of a display screen with an animated graphical user interface showing my new design; and,

FIG. 4 is a front view of a second image thereof.

In the first embodiment, the appearance of the transitional image sequentially transitions between the images shown in FIGS. 1 through 2. In the second embodiment, the appearance of the transitional image sequentially transitions between the images shown in FIGS. 3 through 4. The process or period in which one image transitions to another image forms no part of the claimed design.

The broken line showing of a portion of a display screen and a mobile device in FIGS. 1 through 4 forms no part of the claimed design. The broken line showing of text and portions of the graphical user interface in FIGS. 1 through 4 represents environmental subject matter and forms no part of the claimed design. A portion of the graphical user interface of FIG. 2 is shown as being blurred. Claimed elements and environmental subject matter appearing in the blurred portion of FIG. 2 are, other than being blurred, identical to the claimed elements and environmental subject matter appearing in the same portion of the graphical user interface in FIG. 1. A portion of the graphical user interface of FIG. 4 is shown as being blurred. Claimed elements and environmental subject matter appearing in the blurred portion of FIG. 4 are, other than being blurred, identical to the claimed elements and environmental subject matter appearing in the same portion of the graphical user interface in FIG. 3.

1 Claim, 4 Drawing Sheets
